(57) **CLAIM**

The ornamental design for an apparatus for charging multiple mobile devices, as shown and described.

DESCRIPTION

FIG. 1 is a top plan view of an apparatus for charging multiple mobile devices.

FIG. 2 is a bottom plan view of the apparatus for charging multiple mobile devices of FIG. 1.

FIG. 3 is a side elevational view of the apparatus for charging multiple mobile devices of FIG. 1.

FIG. 4 is an opposing side elevational view of the apparatus for charging multiple mobile devices of FIG. 1.

FIG. 5 is a front elevational view of the apparatus for charging multiple mobile devices of FIG. 1.

FIG. 6 is a back elevational view of the apparatus for charging multiple mobile devices of FIG. 1.

FIG. 7 is top perspective view of the apparatus for charging multiple mobile devices of FIG. 1 with connection cables shown in broken lines; and,

FIG. 8 is a top perspective view of the apparatus for charging multiple mobile devices of FIG. 1 with connection cables and multiple mobile devices positioned within the apparatus shown in broken lines.

The broken lines in the drawings represent the environmental subject matter and form no part of the claimed design.
